S. J. ROSS, DEC'D.
H. SCHOFIELD, ADMINISTRATOR AND EXECUTOR.
LOCK NUT DEVICE.
APPLICATION FILED MAY 13, 1918.

APPLICATION FILED MAY 13, 1918.

Patented Sept. 2, 1919.

UNITED STATES PATENT OFFICE.

SIDNEY JOHN ROSS, DECEASED, LATE OF LONDON, ENGLAND, BY HARRY SCHOFIELD,
ADMINISTRATOR, OF LONDON, ENGLAND.

LOCK-NUT DEVICE.

1,315,160.

Specification of Letters Patent.

Patented Sept. 2, 1919.

Application filed May 13, 1918. Serial No. 234,274.

To all whom it may concern:

Be it known that I, HARRY SCHOFIELD, of 117 and 118 Leadenhall street, E. C. 3, London, England, am the legal administrator and executor of the late SIDNEY JOHN Ross, of the same address, who invented certain new and useful Improvements in or Relating to Lock-Nut Devices, of which the following is a specification.

10 This invention has reference to lock-nut devices which have an eccentric locking action and in which one nut has a plug or spigot part projecting into a recess or socket in the other, the two nuts being connected together to form one unit or device.

15 This invention provides not only an eccentric grip action of the spigot in the socket but retains also the ordinary locking or jamming action of the back-nut against the main nut. Thus the two locking actions supplement one another, giving a double locking. Moreover the eccentric action is obtained in a simple manner by making the bore or eye of the device eccentric. The 20 nuts are so connected that there is between them a slackness or lost-motion equal to a definite fraction of the pitch (say a third or half the pitch of the screw-thread), and also a corresponding gap between the internal threads of the said nuts.

30 One example of construction is shown in the accompanying drawings.

In these drawings:—

Figure 1 is a side-view, and

35 Fig. 2 is a vertical section of such a lock-nut device.

Fig. 3 is an enlarged fragmentary view hereinafter referred to.

40 *a* is the main nut and *b* the back-nut or jam-nut of the improved device.

c is a recess or socket in *a*, which receives a plug or spigot *d* on *b*.

45 *a*¹ and *b*¹ are respectively the screw-threaded eyes or bores, which according to the invention are eccentric to the nuts themselves.

This eccentricity causes *d* to bind or jam (in the known manner) in *c* if the back-nut *b* is turned relatively to *a*.

50 *e* is a groove or recess formed around the top of the plug or spigot part *d* (see Figs. 2 and 3), to receive the bent-over edge *f*¹ of a wedge-like lip *f* around the mouth of the socket *c*.

55 Before the device is screw-threaded, the

nuts are forced down on to each other until the top of the groove *e* bears on the edge of the lip *f* (see Fig. 3) and presses, curls or clenches it inward as indicated at *f*¹ in dotted lines. The lip now projects laterally 60 into the groove in the parts *b* *d*, and thus prevents the nuts becoming separated or detached, although they can still turn relatively to each other. The distance between the bent edge *f*¹ of the lip and the bottom 65 edge *e*¹ of the groove *e*, should be about equal to the gap *g* below the plug *d*.

One or more distance pieces *i* (Fig. 2) may be inserted between the nuts to prevent them being pressed closer together than is 70 required to bend the edge *f*¹.

In practice the plug or spigot *d* and the socket *c* can be easily cut concentrically with the nuts on a lathe, and the undercut groove *e* and lip *f* formed at the same time. The 75 two nuts *a* *b*, are then put under a press and the lip *f* clenched over at *f*¹ as described. The said nuts (now forming one unit) are then bored or tapped eccentrically as at *a*¹ *b*¹ from the bottom end, that is to 80 say from *a* toward *b* at one single operation thus simplifying the manufacture, in contrast to making *c* and *d* eccentric. The lip *f*¹ limits the distance of the nuts at this time, and the thread in the bore *a*¹ (in spite 85 of the gap at *g*) is an exact continuation of that in the bore *b*¹.

The marks *h* are then applied to the nuts, and when opposite each other show that the threads *a*¹ *b*¹ match or correspond exactly. 90

The arrangement is such that when the nuts are on a bolt with the marks *h* in line they can be screwed up freely like one single nut. If *b* is then turned relatively to *a*, it will close the gap *g* and set up an ordinary 95 lock-nut action, at the exact moment at which the part *d* turning in the socket, sets up a circumferential binding or gripping action due to the eccentricity.

This eccentric action should for instance 100 be completed in one-third of a turn, if the gap *g* equals one third of the distance between the screw-threads. Thus the two locking or jamming actions effectually supplement each other, and a double locking 105 action is obtained.

I claim:—

In a double action lock-nut device, the combination of two eccentrically bored and threaded nuts, one of said nuts having a 110

concentric socket and the other having a concentric plug fitting in said socket, said first-named nut having a tapered conical lip around the mouth of said socket, the other 5 of said nuts having a groove at the root of said plug to receive said lip and allow end-wise play, and said nuts having marks to indicate the proper relative position where the threads match and both nuts screw on 10 simultaneously like a single nut, the nuts

having at such time a gap between them which is closed when the back nut is given the necessary extra turn to cause the eccentric locking action, substantially as described.

15

In testimony whereof I affix my signature.

HARRY SCHOFIELD,
Administrator and executor of Sidney John Ross, deceased.
